INKWELL MOUNTING

Loid Crandall, John W. Davis, and Lorentz J. Lindquist, Los Angeles, Calif., assignors to Harry A. Morgan, Los Angeles, Calif.

Application January 10, 1936, Serial No. 58,512

4 Claims. (Cl. 120—58)

This invention relates to an ink well mounting, and has as its primary object the provision of an effective means for affording a connection between the annular base of an ink well and a slab which is so formed as to afford ready engagement and disengagement of the ink well and slab.

Another object is to provide a means for fastening an ink well base to a slab without effecting positive engagement with the latter, and which while affording a secure connection between the ink well and the slab will permit of ready detachment and replacement of the ink well.

15 While the invention is applicable for use in connection with slabs of various materials, it is especially designed to be applied to slabs of marble, glass, stone, and similar hard and brittle materials which are difficult to work to form a positive connection therewith; the present invention contemplating a means for affording a frictional grip between a smooth bore in the slab and smooth periphery of an ink well base.

With the foregoing objects in view, together 25 with such other objects and advantages as may subsequently appear, the invention resides in the parts and in the combination, construction and arrangement of parts hereinafter described and claimed, and illustrated by way of example 30 in the accompanying drawing, in which:

Fig. 1 is a perspective view of a ring clamping element;

Fig. 2 is a detail in cross section taken on the line 2—2 of Fig. 1;

35 Fig. 3 is a perspective view showing an ink well mounted on a slab in accordance with the invention;

Fig. 4 is a detail in section taken on the line 4—4 of Fig. 3.

40 Referring to the drawing more specifically, A indicates a slab formed of any suitable solid material having a circular opening 6 formed therein and which slab may be covered on its under side with a sheet padding 7 formed of felt or similar material and which sheet may extend over the opening 6, as particularly shown in Fig. 4.

An ink well B formed with a cylindrical base 8 is designed to be mounted in the opening 6; the base 8 being formed with an outwardly extending 50 marginal flange 9 on its lower edge having an external diameter slightly less than the diameter of opening 6. Mounted on the upper portion of the cylindrical base 8 is an outwardly and downwardly extending flange 10 the outer margin of which

is adapted to seat on the upper face of the slab A.

In carrying out the invention, a split ring C is provided. The ring C is formed of a strip of resilient sheet metal, so as to have a spring action and is formed of a normal diameter exceeding the diameter of the opening 6 and is adapted to be contracted and inserted in the opening 6 and allowed to expand therein whereby its outer periphery will effect frictional engagement with the walls of the opening 6.

Formed on the ring C and extending transversely thereof from adjacent its upper margin is a series of vertically extending spring tongues 11, (assuming the ring to be disposed horizontally) the connecting end portions of which tongues protrude inwardly and downwardly from the inner periphery of the ring and the lower free end portions of which terminate in inwardly spaced relation to the inner periphery of the ring as particularly shown in Fig. 2.

In the application and operation of the invention, the spring C is positioned in the opening 6 whereupon the cylindrical base of the ink well B is inserted in the ring with the flange 9 thereof bearing against the tongues 11; the outer periphery of the flange 9 being of a diameter exceeding that of a circular line defining the faces of the inwardly projecting connected end portions of the tongues 11 so as to snap by the connected end portions of the tongues and thereafter press the free ends of the tongues toward the inner periphery of the ring, thereby collectively placing the tongues under tension and causing the tongues to grip the flange 9 and at the same time exert outward radial thrusts on the ring C such as to augment the pressure of the ring against the wall of the opening 6. The upper connecting end portions of the tongues 11 will then overlie the marginal flange 9 on the ink well and will then act to yieldably oppose separation of the ink well base and the split ring. In thus positioning the ink well in the opening 6 the flange 10 thereon is disposed to bear upon the top face of the slab A adjacent the margin of the opening so as to extend over the upper edge of the ring 6 and the gap between the inner periphery thereof and the outer perimeter of the base 8 thus concealing the spring ring and affording a neat finish.

It will now be seen that the spring ring will afford a grip between the ink well and the slab which while holding the ink well against accidental displacement will permit of ready re-

moval of the ink well from the base when occasion requires; since on applying an upward pull on the ink well sufficient to overcome either the resistance offered by the spring tongues or the frictional engagement of the ring with the margin of the opening in the slab the ink well will be lifted clear of the slab. Where the resistance of the tongues exceeds the resistance to sliding of the ring on the wall of the opening in the slab 10 the ring will be withdrawn from the slab with the ink well.

We claim:

1. In an ink well mounting, a slab formed with a circular opening, an ink well having a cylindrical base formed with an outwardly extending flange on its lower margin, said base being disposed in said opening, a resilient ring interposed between the wall of said opening and the outer periphery of said flange, and a series of spring tongues on said ring projecting inwardly therefrom engaged by the outer periphery of said flange and placed under tension thereby; said tongues having their connected end portions projecting over the upper edge of said flange.
2. In an ink well mounting, a slab formed with a circular opening, an ink well having a cylindrical base formed with an outwardly extending flange on its lower margin, said base being disposed in said opening, a resilient ring interposed between the wall of said opening and the outer periphery of said flange, and a series of spring tongues struck from said ring and projecting inwardly and downwardly therefrom said flange bearing against said tongues intermediate their ends with the tongues placed under tension there-

by, and a flange on said ink well seating on the upper face of said slab.

3. In an ink well mounting, a slab formed with an opening, a split ring slidably seated on the wall of said opening in frictional engagement therewith, a series of spring tongues struck from said ring and projecting inwardly and downwardly therefrom with their connecting portions leading from adjacent the upper margin of said ring; and an ink well base inserted in the space bounded by said ring, a marginal flange on said base slidably engaging said spring tongues intermediate their ends; said tongues being placed collectively under tension by pressure of said base flange thereon and acting to press said ring into frictional engagement with the wall of said opening.

4. In an ink well mounting, a slab formed with an opening, a split ring seated on the wall of said opening, a series of spring tongues struck from said ring projecting inwardly therefrom with their connecting portions leading from adjacent the upper margin of said ring, an ink well base inserted in the space bounded by said ring, a marginal flange on said base having its periphery engaging said spring tongues intermediate their ends; said tongues being placed collectively under tension by pressure of said base flange thereon and acting to press said ring into engagement with the wall of said opening; the connecting portions of said tongues having their innermost faces overlying the marginal flange to resist withdrawal of the ink well from said ring.

LOID CRANDALL.

JOHN W. DAVIS.
